[57] CLAIM

The ornamental design for a vacuum cleaner, as shown and described.

DESCRIPTION

FIG. 1 is a top, front and left side perspective view of a vacuum cleaner showing my new design;

FIG. 2 is a top, rear and left side perspective view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top plan view thereof;

FIG. 8 is a top, rear and left side perspective view in operation; and

FIG. 9 is a top, front and right side perspective view thereof.

The centrifugal separator shown in broken lines in FIGS. 1, 4 and 5 is for illustrative purposes only and forms no part of the claimed design.
